CLAIM

The ornamental design for a hanging bag, as shown and described.

DESCRIPTION

FIG. 1 is a perspective view of my new design, showing a hanging bag;

FIG. 2 is another perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged partial view of a part enclosed 9 in FIG. 1; and,

FIG. 10 is an enlarged partial view of a part enclosed 10 in FIG. 2.

The dash-dot-dash broken lines are for the purpose of depicting the boundary line of the enlarged view and form no part of the claimed design.

1 Claim, 10 Drawing Sheets
